(57) CLAIM

The ornamental design for an undergarment as shown and described.

DESCRIPTION

FIG. 1 is a top, front, right perspective view of a first embodiment of the claimed design for an undergarment; FIG. 2 is a top view thereof; FIG. 3 is a bottom view thereof; FIG. 4 is a front view thereof; FIG. 5 is a rear view thereof; FIG. 6 is a left side view thereof; FIG. 7 is a right side view thereof; FIG. 8 is an enlarged partial view of FIG. 2 with unclaimed subject matter omitted; FIG. 9 is a top front, right perspective view of a second embodiment of the claimed design for an undergarment showing an alternative configuration; FIG. 10 is a top view thereof; FIG. 11 is a bottom view thereof; FIG. 12 is a front view thereof; FIG. 13 is a rear view thereof; FIG. 14 is a left side view thereof; FIG. 15 is a right side view thereof; and, FIG. 16 is an enlarged partial view of FIG. 10 with unclaimed subject matter omitted. The uneven-length broken lines are imaginary lines that depict boundaries of the claimed design and form no part thereof. The even-length broken lines showing the remainder of the undergarment depict environmental structure and form no part of the claimed design.
